DOOR LATCH

Filed May 14, 1927

UNITED STATES PATENT OFFICE.

HARRY E. WOERNLE, OF PITTSBURGH, PENNSYLVANIA, ASSIGNOR TO MCKINNEY MANUFACTURING COMPANY, OF PITTSBURGH, PENNSYLVANIA, A CORPORATION OF PENNSYLVANIA.

DOOR LATCH.

Application filed May 14, 1927. Serial No. 191,374.

My invention relates to door latches and locks, and more particularly to a latch device of the silent type, whereby a door may be pushed to closed position and yieldably held in such position, without clicking or other sound. The invention is especially useful in connection with the doors of hospitals, hotels, apartment houses, etc.

One object of my invention is to provide a door latching and locking unit of improved form, and capable of application to doors, without materially altering the structure of such doors.

Another object of my invention is to provide a latching device that is noiseless in operation.

Another object of my invention is to provide a latching device of the silent type that is readily adjustable, but which is rigidly supported against movement independently of the adjusting means.

Still another object of my invention is to simplify and improve door-holding devices generally.

Some of the forms which my invention may take are shown in the accompanying drawing, wherein Figure 1 is a perspective view of a door-latching and locking unit, removed from a door; Fig. 2 is a perspective view of a keeper plate which the lock bolt of Fig. 1 engages when in operative position; Fig. 3 shows a co-operating keeper or striker for the latch device of Fig. 1; Fig. 4 is a perspective view, showing the latching device independently of the lock of Fig. 1; Fig. 5 is a view taken on the line V—V of Fig. 6, and showing the latching members of Figs. 3 and 4 in position in a door structure, and Fig. 6 is a view taken on the line VI—VI of Fig. 5.

In Fig. 1, I have shown a door lock 7 which may be of any usual form for insertion in the edge of a door in the usual manner. The bolt 8 of the lock co-operates with a keeper or striker plate 9 that may be mounted on a door jamb such as shown in Figs. 5 and 6.

The lock 7 is secured to a face plate 10 in any suitable manner. The face plate, near its lower end has a rectangular casing 11 formed integrally therewith or fastened thereto by welding or in some other manner. A block 12 extends into the casing 11, through the rear end thereof, and has ver-

tically spaced tongues 13 that project through an opening in the face plate 10. Screws 14 extend loosely through the face plate and have threaded engagement with the upper and lower end of the block 12. Compression springs 15 surround the screws 14 and exert sufficient pressure to hold the heads of the screws in snug engagement with the face plate 10. The screws 14 serve as a means of adjustment whereby the block 12 can be shifted longitudinally of the casing 11, to cause the tongues 13 to project forwardly of the face plate 10 a desired distance.

A latch head 16, preferably in the form of a rubber roller is supported between the tongues 13 (as shown more clearly in Fig. 5) by means of a pin 17 that may be screwed or riveted in position. The screws 14 are so adjusted that the latch head 16 will project far enough to engage a depression in a striker plate or keeper 18 which is fastened to a door jamb 19, when the door 20 which carries the latch is moved to closed position, as shown more clearly in Fig. 6.

The latch device 16, being of rubber, is not only noiseless, but will yield sufficiently to enable it to pass from the outer reduced edge of the striker plate 18 over an intermediate raised portion and into the depression near the mid portion of said plate. It will be understood that instead of providing a depression in the plate 18, a protuberance could be formed thereon in position to engage the roller and releasably hold the door against swinging open.

The screws 14 serve as tie bolts, to rigidly hold the block 12 which carries the roller, against movement when the roller engages the striker plate, thus avoiding clicking noises such as would occur if the roller or its supporting block were backed by a spring. The springs 15 are normally inactive and serve merely to hold the heads of the screws 13 in their seats and the block 12 in its rear-most position, there ordinarily being no force tending to move the block 12 forwardly, except when the screws 14 are turned to effect adjustment of the latch head 16 toward the striker plate.

The casing 11 may be dispensed with, but I prefer to employ the same as a guiding and supporting element for the block 12 which

has a sufficiently snug fit therewith to avoid clicking noise when the roller 16 engages the striker plate.

I claim as my invention:—

- 5 1. Latch structure comprising a face plate, a block disposed rearwardly of said plate and having a nose portion extending therethrough, and an adjusting screw rotatable in said plate and having threaded engagement with said block to vary the extent to which the said nose portion extends through the plate.
- 10 2. Latch structure comprising a face plate, a pair of adjusting screws rotatably supported by said plate and extending therethrough, a block having a nose portion extending through the face plate at a point between the said screws and having threaded engagement with the screws.
- 15 3. Latch structure comprising a face plate having an opening therethrough, a casing open at its rear side and disposed against the rear face of said plate, a block extending into said casing and having a nose portion 20 extending to the front of the plate, and adjustable means for rigidly supporting said block against rearward movement relative to said casing.
- 25 4. Latch structure comprising a face plate having an opening therethrough, adjusting

screws supported by said plate and extending therethrough, a block having threaded engagement with the screws and normally spaced from the face plate and a yieldable latch head carried by said block and normally extending through said opening, at a point between the said screws.

35 5. Latch structure comprising a face plate, a block extending rearwardly of said face plate and normally spaced therefrom, a yieldable latch head carried by the forward end of said block, and an adjusting screw rotatably supported in said plate and having threaded engagement with the block, to vary the position of said head with respect to the 40 face plate.

6. Latch structure comprising a face plate, a block extending rearwardly of said face plate, a yieldable latch head carried by the forward end of said block, an adjusting screw rotatably supported in said plate and having threaded engagement with the block, to vary the position of said head with respect to the face plate, and means for preventing outward movement of the screw 45 with respect to the face plate.

In testimony whereof I, the said HARRY E. WOERNLE, have hereunto set my hand.

HARRY E. WOERNLE.
